FOOT ARCH SUPPORT

Percival George Hamlyn Hinder, London,
EnglandApplication January 4, 1930, Serial No. 418,589
In Great Britain January 7, 1929

5 Claims. (Cl. 36—71)

This invention relates to foot arch supports the underside of which is so hollowed that at some part or parts a relatively narrow edge is presented to the inner sole of foot-wear with 5 which the supports are used.

It has heretofore been proposed to provide a protective device, such as a bearing plate or covering of metal, leather or other material, to prevent or reduce chafing and wear of the inner sole of foot-wear to which the arch supports 10 are applied.

The protective devices hitherto proposed have either been permanently attached to the underside of the foot arch support by rivets or similar 15 means or they have been formed in a pocket shape into which the end of the support was inserted.

The object of the present invention is to provide a protective device for the above mentioned 20 purpose and means for attaching it to the foot-arch support, which shall be simple to manufacture and shall overcome the disadvantages of the above mentioned types by being readily removable from the foot-arch support without adding 25 unduly to the thickness of the support.

Some of the forms which the invention may take are illustrated in the accompanying drawings in which

Figure 1 is an underside plan view of one form 30 of foot-arch support.

Figure 2 is a section on the line A—A of Figure 1,

Figure 3 is a side elevation of the foot-arch support shown in Figure 1,

Figure 4 is an underside plan view of another 35 form of foot-arch support,

Figure 5 is a longitudinal section through a further form of foot-arch support,

Figure 6 is a plan view of the foot-arch support shown in Figure 5,

Figure 7 is an underside plan view of a foot-arch support provided with a leather covering,

Figure 8 is an enlarged perspective view of one of the attaching studs,

Figure 9 is a similar view of one of the hooks 45 which may replace the attaching studs.

In the form of the invention illustrated in Figures 1, 2 and 3, two studs c1 and c2 (see Figure 8) are provided rigidly fixed to the underside of the metal or like plate a of the foot-arch support near the edge a1, which it is desired to prevent from bearing on the inner sole of the foot-wear. These studs provide anchorage for 50 a protective device b of leather, fibre, flexible metal or other suitable material provided with

slots b1 and b2, located to register with the studs c1 and c2 respectively, and so shaped that its edge b3 projects beyond the edge a1 of the arch support plate. The edge b3 of the protecting pad is suitably skived.

The protecting pad b is similarly shaped on each side of the line joining the studs c1 and c2, so that when one edge is worn the pad may be removed, turned round in its own plane and replaced so that the slot b1 registers with the 60 stud c2 and the slot b2 with the stud c1. A fresh protecting surface is thus presented to the edge of the plate a.

In a foot-arch support of the type shown in Figure 4 the greatest breadth of the plate a is 70 very near the front edge and if a reversible pad of the shape shown in Figures 1, 2 and 3 were used it would project far beyond the sides of the plate. In this case an alternative wearing surface for the edge of the plate a is provided by forming the 75 pad b with a second pair of slots b4 and b5, immediately in rear of the slots b1 and b2. A fresh bearing surface for the plate may thus be provided by moving the pad b forward, so that the studs c1 and c2 register with the slots b4 and b5. 80

In cases where support for the transverse metatarsal arch is required the form of foot-arch support shown in Figures 5 and 6 may be used. A strip of leather or other suitable material d, overlying the plate a, is attached by its front edge d3 85 to the front edge b3 of the protecting pad b. The rear portion of the strip d is split to form flaps d1 and d2 and a pad e of horse hair, rubber, felt or other suitable material inserted between the flaps. The rear edges of the flaps d1 and d2 90 are skived on their inner and outer surfaces to make a smooth joint with the upper surface of the plate a. Alternatively a pocket for the pad e may be formed by stitching to the underside of the overlying strip a further layer of fabric or 95 other material. Additional clips f1 and f2 are provided to keep the overlying pad flat on the plate a.

In the type of foot-arch support shown in Figure 7, in which the plate a has attached to its 100 upper side by rivets h1, h2, and h3, a leather or like covering g, the pad b may be attached to the plate by a metal clip j2 placed over the shank of the rivet h2 before the rivet is set down. A second similar clip j3 is attached to the plate by a 105 rivet h3. The clips j2 and j3 co-operate with slots k2 and k3 cut in the pad b.

By making the slots in the protecting pad wider than the clips or studs on the plate a sliding motion between the plate and the protector takes 110

place during wear, which adds to the life of the protector as the edge of the plate, instead of bedding itself into the protecting pad, creates a hard polished surface on the pad.

5 It has been found of advantage to compress the substance of that part of the protector which slides beneath the head of the studs or clips. This enables the height of the studs or the like to be reduced so that they avoid contact with the inner 10 sole of foot-wear in which the foot-arch supports are used.

The studs may be replaced by hooks c3 (see Figure 9) which co-operate with indentations on the edge of the protecting pad.

15 What I claim and desire to secure by Letters Patent is:—

1. A foot arch support comprising a plate, a protecting pad underlying the forward edge thereof, and means for removably securing said pad to the underside of said plate in any one of a plurality of positions in each of which a different part of the pad is presented to the forward edge of the plate, said means being such that a worn pad may readily be replaced by the user.

25 2. A footarch support comprising a metal plate, headed studs secured to the underside of the said plate close to the forward edge thereof, a protecting pad underlying the forward edge of the plate, and slots in the edges of the pad adapted to co-

operate with the headed studs to removably secure the pad to the plate.

3. A foot arch support comprising a metal plate, headed studs secured to the underside of the said plate close to the forward edge thereof, a protecting pad underlying the forward edge of the plate, and slots in the edges of the pad adapted to co-operate with the headed studs to removably secure the pad to the plate in any one of a plurality of positions in each of which a different part of the pad is presented to the forward edge of the plate.

4. A foot arch support comprising a plate, a protecting pad underlying the forward edge thereof, a strip of material secured to said pad and overlying said plate, a support for the transverse metatarsal arch carried by said strip of material, and means on the underside of said plate and cooperating means on said pad for removably securing said pad to the underside of said plate, said means being such that a worn pad may readily be replaced by the user.

5. A foot arch supporting plate, a flexible pad therefor and means, comprising projecting studs on the plate and cooperating apertures in the pad, for removably securing the pad to the underside of the plate.

PERCIVAL GEORGE HAMLYN HINDER.
